UNITED STATES PATENT OFFICE

135,246

DESIGN FOR A COMBINED COLLAPSIBLE TUBE AND DISPENSING CLOSURE THERE- FOR

Wilfred H. Burke, Hutchinson, Kans.

Application August 17, 1942, Serial No. 107,952

Term of patent 3½ years

To all whom it may concern:

Be it known that I, Wilfred H. Burke, a citizen of the United States, residing at Hutchinson, in the county of Reno and State of Kansas, have invented a new, original, and ornamental Design for a Combined Collapsible Tube and dispensing Closure Therefor, of which the following is a specification, reference being had to the accompanying drawing, forming part thereof.

Fig. 1 is a side view of a combined collapsible tube and dispensing closure therefor, showing my new design;

Fig. 2 is a side view transverse to that shown in Fig. 1;

Fig. 3 is a top plan view of the cap portion only of the combined collapsible tube and dispensing closure therefor, the tube portion being omitted for convenience of illustration.

I claim:

The ornamental design for a combined collapsible tube and dispensing closure therefor, substantially as shown and described.

WILFRED H. BURKE.
